UNITED STATES PATENT OFFICE

2,228,322

LUBRICATING UNIT

Victor A. Miller, Duluth, Minn., assignor of one-half to Charles S. Olson, Duluth, Minn.

Application January 20, 1940, Serial No. 314,805

5 Claims. (Cl. 184—13)

This invention relates to an improved lubricating unit and method of lubrication, and has special reference to such a unit and method particularly adapted for the lubrication of the geared surfaces of intermeshing power transmission means such as the heavy duty gears used in driving coal pulverizers, ore graders, rotary dry kilns, stone crushers, or the like.

In such transmission means there is usually employed a relatively small driving pinion meshing with a much larger gear, and it is well known that the matter of adequate and uniform lubrication for such intermeshing surfaces is very important, and that irrespective of the type of gear employed, i. e., spur, helical, herringbone, or the like.

The principal object of the instant invention is to overcome many of the disadvantages of the present system of such lubrication, as well as provide as simple a device as possible for the purpose.

Another object is to overcome waste of lubricant as by dripping, splashing, or the like, as well as provide convenient means for inspection of the gears when desired.

Other objects and advantages of the invention will appear in the following description thereof.

Referring now to the accompanying drawing, forming part of this application, and wherein like reference characters indicate like parts:

Figure 1 is a side elevation of the invention as applied to a pair of gears, and Figure 2 is a front elevation of Figure 1.

In the drawing the numeral 1 represents the smaller driving pinion, 2 the larger driven gear, such as is commonly found in the arts above referred to, and 3 represents the pedestal upon which the pinion shafts 4 is carried.

Upon the pedestal 3 and beneath the pinion 1 is mounted a trough like receptacle, the end walls of which are illustrated at 5 and constructed of suitable sheet metal for the purpose, as is also the arcuately shaped trough-like bottom 6, the same being spaced slightly below the lower surface of the pinion and extending upwardly substantially as illustrated both in the rear and in front of the pinion, the rear portion preferably extending vertically to about a level with the top of the pinion, as at 7. To the lower portion of this rear wall is attached a relatively narrow auxiliary feeding trough, the upwardly arched bottom of which is illustrated at 8, and the end walls at 10. This auxiliary trough communicates with the larger trough preferably as

by elongated openings indicated at 9, thus providing convenient means for feeding lubricant to the unit at any time.

The wall 7 is designed to extend materially above the end walls 5 of the unit as clearly illustrated in Figure 1, and back of this extension and above same is designed to be pivotally mounted a shield or baffle plate indicated at 11, which, just above the upper edge of the wall 7, is inclined inwardly towards the gears 1 and 2. Just above the upper edge of the wall 7 the baffle 11 is provided with a drip moulding or angle indicated at 12, the same being disposed transverse the baffle to function as a guard against any lubricant which may be splashed upwardly or against the baffle 11 above the wall 7 dripping downwardly and backwardly of said wall; the same being thus conveyed back into the trough.

The baffle 11 is reinforced and supported as by suitable channel bars indicated at 13, one upon the back face of either end thereof, and which bars extend downwardly to approximately a level with the bottom of the trough 6 and there each connected as at 14 to one end of a contractile helical spring indicated at 15, while spaced above such spring connection are through holes within the backwardly extending flange of each angle 13 for the reception of the through rod 16 which also extends through the end walls 5 of the trough to act as a pivotal support for the baffle 11. This baffle 11 is cut-away in the lower portion thereof as indicated at 17 so that the baffle may be readily pulled backwardly over the auxiliary trough 8 for inspection of the gears and their condition, at any time.

It will be noted that the angles 13 are positioned with their projecting flanges inwardly in respect to the baffle 11, resulting in a quite convenient construction of the unit, in that the holding flanges 18 of the end walls 5 also extend inwardly with the object of the unit employing as narrow a space as possible, and that the holding bolts indicated at 19 of the unit may also function as holding means for the extending strips 20, each carrying an upstanding lug 21 to which the opposite end of the contractile springs 15 are attached so that their pulling force tends to normally hold the baffle in operative position as shown in Figure 1 of the drawing. This baffle is seen to be supplied with a suitable handle indicated at 22 for convenient manipulation of same for the purpose previously described.

It is also to be noted that the end walls 5 of the unit are shaped in the peculiar manner

- shown, that is with the inner portions thereof extending well inwardly of the pinion shaft as well as the front wall extending above the shaft 4 of the pinion, the same being to insure against 5 any possibility of the unit being drawn inwardly and engaging the gears in the event of the same working loose, as it is well known such large gears while in operation present a hazard well to guard against.
- 10 Having thus described my invention, what I claim and desire to secure by Letters Patent, is:
1. A lubricating unit for a pinion driving a larger gear comprising in combination a trough-like structure about the lower and front portion 15 of said pinion, end walls for said trough extending beneath and upwardly in front of the shaft of said pinion, an auxiliary smaller trough extending forwardly of said end walls and communicating with said first trough, the front wall 20 of said first trough extending upwardly above said auxiliary trough and in front of said pinion, and a splash board pivotally carried in the forward edge of said end walls and extending inwardly and above said front wall of said first 25 trough, and resilient means for normally holding said splash board in operative position.
  2. A lubricating unit for heavy intermeshing gears or the like wherein a relatively small driving pinion is employed for driving the larger gear, comprising in combination a trough-like housing 30 about the lower portion of said pinion, an upright shield pivotally mounted transverse the front portion of said trough and extending above a horizontal plane with the top of said pinion, said 35 trough characterized by having an extension through and in front of said shield whereby to receive a lubricant forwardly of said shield.

3. A lubricating unit for heavy intermeshing gears or the like wherein a relatively small driving pinion is employed for driving the larger gear, comprising in combination a housing about the lower portion and front of said pinion, means for 5 receiving and conveying a lubricant to the bottom of said housing from in front of said housing, and means adjustably carried by said housing and extending above the top of said pinion to prevent splashing of lubricant outside of said housing. 10

4. A lubricating unit for heavy intermeshing gears or the like wherein a relatively small driving pinion is employed for driving a larger gear, comprising in combination a housing about the lower portion and front of said pinion, a lateral 15 inclined feeding trough extending from said housing to a point remote from said pinion, whereby lubricant may be supplied to said trough to flow by gravity to the bottom of said housing, and means adjustably carried by said housing and 20 extending above the top of said pinion to prevent splashing of lubricant outside of said housing.

5. A lubricating unit for heavy intermeshing gears or the like wherein a relatively small driving pinion is employed for driving a relatively large 25 gear, comprising in combination a housing about the lower portion and front of said pinion, means for receiving and conveying a lubricant to the bottom of said housing from in front of said 30 housing, means adjustably carried by said housing 30 and extending above the pinion to prevent splashing of lubricant outside of the housing, and means for biasing said last mentioned means in normal operative position.

35 VICTOR A. MILLER.
